Fig. 1. Drawing of a horse's head and neck with various numbered parts labeled 1 through 30. The drawing shows a side profile of a horse's head and neck. Numbered labels include: 25 (ear), 29 (bit), 13 (poll), 30 (mane), 23 (tail), 27 (ear), 12 (ear), 1 (nose), 14 (lower jaw), 16 (lower jaw), 15 (lower jaw), 21 (ear), 4 (ear), 6 (ear), 8 (ear), 5 (ear), and 2 (ear). The drawing uses hatching to indicate shading and texture.

A technical line drawing of a mechanical assembly, likely a cylinder or actuator. The drawing shows a central vertical rod (1) with a piston (2) at the bottom. A U-shaped tube assembly (3) is attached to the rod. On the left side, there is a complex assembly of components labeled 11 through 29. A horizontal rod (16) is attached to the left side of the assembly. On the right side, there is a cylinder body (5) with a handle (15) and a rod (10) extending from it. Various other parts like 4, 6, 7, 8, 9, 12, 13, 14, 17, 18, 23, 27, and 28 are also labeled. The drawing uses a combination of solid lines for structural parts and dashed lines for internal or less prominent features.

UNITED STATES PATENT OFFICE.

NELS MADSON, OF COEUR D'ALENE, IDAHO.

WHEELED TOY.

Application filed August 24, 1926. Serial No. 131,235.

My present invention has reference to a wheeled toy designed to provide both amusement and healthy exercise for children.

My object is the provision of a toy of this character shaped to represent a horse or similar animal, mounted on wheels, propelled by the operation of foot pedals and arranged in a manner whereby the turning of the wheels will impart a reciprocatory movement in a vertical direction to the body so that the toy, when propelled, will have imparted to its body portion a movement similar to the loping, galloping or bucking of a horse, and further wherein means is provided for steering the toy.

To the attainment of the above broadly stated objects and many others which will present themselves as the nature of the invention is better understood, the improvement further resides in certain novel features of construction, combination and operative association of parts, a satisfactory embodiment of which is disclosed by the accompanying drawings.

In the drawings:

Figure 1 is a side elevation of a wheeled toy in accordance with this invention.

Figure 2 is a bottom plan view thereof.

Figure 3 is an approximately central vertical longitudinal sectional view through the toy.

Figure 4 is a front elevation thereof.

Figure 5 is a sectional view on the line 5—5 of Figure 3.

In carrying out my invention I make use of a substantially rectangular frame 1. Journalized in suitable bearings in the bottom of the frame 1 there are front and rear shafts 2 and 3, respectively. The ends of the shaft 2 are cranked and provided with front pedals 4, while on the ends of the shaft 3 there are fixed ground wheels 5. Both the shafts 2 and 3 have oppositely directed crank portions 6 and 7, arranged between the side members of the frame, and the cranks of the respective shafts are connected by the usual connecting rods 8.

It will be apparent that by revolving the shaft 2 a like movement will be imparted to the shaft 3 for turning the wheels 5. In addition to the cranks 7 the shaft 3 is provided with a central offset or crank portion 10, the purpose of which will presently be apparent.

The side members of the frame 1 have

their front ends extended beyond the forward transverse connecting bar or plate 11 for the frame, and these extending ends have secured on their upper edges a transverse plate 12. Passing through a bearing opening in the plate 12 there is the threaded end of a crank rod 13. Secured to the straight threaded end of the said crank rod 13 there is a yoke 14, and journaled through the parallel arms of the yoke 14 there is a shaft 15 for the steering wheels 16. The steering wheels are arranged inwardly with respect to the propelling wheels 5 and are smaller than the said propelling wheels. The straight threaded portion of the crank rod 13 is engaged by suitable nuts 17 which preferably contact with both the upper and lower faces of the bar or plate 12, and secured to the transverse element 11 of the frame 1 or to a cleat 18 that is fixed on the said element 11 there is the offset end of an outwardly directed plate 19 through which the straight inner end of the crank rod 13 passes.

Arranged over the frame 1 there is the hollow body 20 of a figure shaped to represent a horse or similar animal. The sides of the body 20 are approximately centrally pivoted to the sides of the frame 1 through the medium of a transversely extending rod 21, and loosely secured and mounted on the central crank portion 10 of the shaft 3 there is a rod or pitman 22 which is pivoted through the medium of a transversely extending rod 23 to the rear of the body 20. The forward end of the body has pivotally secured thereto, as at 24, a head portion 25, the said head portion being shaped to represent the head of a horse or like animal. The head 25 is also hollow and the mouth portion thereof has passed therethrough a rod 26. Centrally fixed on this rod 26 there is an arched yoke 27, the said yoke preferably comprising two spaced members whose outer or free ends are connected, as at 28. The yoke 27 receives therethrough the upper angle portion 29 of the crank rod 13. The outer ends of the rod 26 are provided with eyes for the reception of rings to which are connected the ends of a strap of leather or similar material, indicated by the numeral 30. The strap represents the rein for the bridle of the representation of the animal and it will be apparent that the rider of the toy, pulling on either of the leads of the strap will swing the head 25, and by virtue of such swinging will move the yoke 27 to turn the

crank rod 13 and consequently turn the yoke 14 on which is journaled the shaft 15 for the wheel 16, so that the toy can be easily steered. It is, of course, to be understood 5 that the U-shaped member 14 which I have termed a yoke, is fixedly secured to the crank rod 13. It will be further apparent that as the toy is propelled by the operation of the pedals the crank shaft 3, through the 10 medium of the pitman 22 and the pivotal connection 24 of the body 20 with the frame, will impart a reciprocating movement in a vertical direction to the body 20, thus causing the body of the toy to represent the loping, bucking or galloping of a horse or like 15 animal.

The improvement is of a comparatively simple construction which may be cheaply manufactured and which will afford both 20 amusement and exercise to the user thereof. The nature of the invention necessarily renders the same susceptible to changes and modifications and, therefore, it is to be understood that I am not to be restricted to the 25 precise details of construction herein set forth and may make such changes therefrom as fairly fall within the scope of the appended claims.

Having described the invention, I claim:

30 1. A wheeled toy as herein described, comprising a frame, spaced transversely arranged shafts journaled on the frame, ground wheels fixed on the ends of one of the shafts, the second shaft having cranked 35 ends and provided with pedals, means between the shafts for imparting motion to the wheel carrying shaft when the pedal carrying shaft is turned, steering wheels between the forward ends of the frame, a mount 40 therefor, a pivotally supported cranked rod associated with the mount and extending above the frame, a hollow body representing

the figure of a galloping horse arranged over the frame and having its sides pivotally secured to the sides of the frame, means 45 operated by the turning of the wheel carrying shaft for imparting a vertical reciprocating movement to the hollow body, a head pivotally secured on the body, a strap having its ends secured to the sides of the head, 50 and an arched yoke fixed to the head, depending therefrom and receiving the cranked rod therethrough, for the purpose set forth.

2. A toy including a substantially rectangular frame, front and rear shafts journaled transversely on the bottom of the frame, ground wheels fixed to the ends of the rear shaft, the front shaft having its ends cranked and provided with pedals, means 60 between the shafts whereby the turning of the pedal shaft will impart a like turning to the wheel carrying shaft, said last mentioned shaft having a cranked portion, steering wheels arranged between the sides of the 65 frame at the front thereof, a mount for the steering wheels, a cranked rod pivotally supported on the frame and associated with the mount, a guide element for the crank rod secured to the frame, a hollow body representing 70 the figure of a galloping horse arranged over the sides of the frame and centrally pivoted to said sides of the frame, a pitman pivoted in the rear of the body and mounted on the cranked portion of the wheel 75 shaft, a head pivotally secured on the forward end of the body, a strap representing a rein having its ends secured to the sides of the head, and an arched yoke depending from the head and receiving between the 80 arms thereof the mentioned crank rod, for the purpose set forth.

In testimony whereof I affix my signature.
NELS MADSON.
